AUTOMATIC BULLET PULLER

William K. Wicks, 210 W. Main, Lewistown, Mont.

Filed Sept. 10, 1958, Ser. No. 760,156

3 Claims. (Cl. 86—23)

The present invention relates to an automatic bullet puller and has for an object the provision of a device of this kind which is capable of being adjustably mounted on a conventional type of bullet reloading tool or cartridge reworking device without the necessity of making any changes in the conventional tool or device.

Another object of the present invention is to provide a bullet puller in which the clamping device will be spread by the upward movement of the cartridge upon the initial operation of the bullet reloading tool for receiving the bullet therein and in which the clamping device will be automatically forced into tight frictional engagement with the bullet upon subsequent movement of the bullet reloading tool.

A further object of the present invention is to provide a device of this character in which an indefinite number of bullets may be pulled from their cartridges or shells without dismantling the bullet puller and without requiring any adjustments of the bullet puller.

The present invention aims to provide a bullet puller which includes means for mounting the bullet puller upon a conventional bullet reloading tool in adjustable relation thereto so that the one and same bullet puller may be used for cartridges of different calibers.

It is well known that a large number of rifle shooters as well as those who shoot pistols and revolvers have made it a practice and sometimes a form of hobby to reload their own ammunition. These users of firearms find it necessary to separate the bullets from the loaded cartridge or shell in order to reduce the load for safe firing or they may desire to pull the bullets from military ammunition thereby making it possible to salvage the cases or bullets or the components thereof. In performing this type of operation, it is of major importance that no damage is done to either the bullet or the cartridge. The present invention contemplates providing a bullet puller which may be safely and easily used by amateurs as well as professionals so that the bullets are separated from the shells in a speedy and efficient manner by a relatively simple operation by the use of a device which comprises a minimum of parts.

With the foregoing and other objects in view, the invention will be hereinafter more fully described and more particularly pointed out in the appended claims.

In the drawings in which the same parts are denoted by the same reference numerals throughout the several views,

Figure 1 is a perspective view of the improved bullet puller constructed in accordance with the present invention and illustrated as applied to a conventional bullet reloading tool,

Figure 2 is a sectional view on an enlarged scale taken on the line 2—2 of Figure 1,

Figure 3 is a view similar to Figure 2 but showing the bullet puller in its bullet engaging position,

Figure 4 is an exploded side elevational view of the improved bullet puller,

2

Figure 5 is a sectional view on an enlarged scale taken on the line 5—5 of Figure 3,

Figure 6 is a sectional view on an enlarged scale taken on line 6—6 of Figure 3,

5 Figure 7 is a bottom plan view of the gripping device, and

Figure 8 is a bottom plan view of a modified form of gripping device.

Referring more particularly to the drawings and es- 10 pecially to Figure 1, A indicates generally the bullet puller of the present invention and B generally indicates a bullet reloading tool or cartridge reworking device to which the bullet puller has been applied. The bullet reloading tool B is shown secured to a work table or

15 other support 10 by fastening elements 11 which may be in the form of conventional bolts and nuts. The tool B comprises a substantially semi-circular portion 12 having the end of one arm 13 provided with a screw threaded bore 14. A flange 15 extends from the semi- 20 circular portion 12 and rests upon the work table 10 and the bolts 11 extend through the work table and the flange 15. Formed integrally with the semi-circular portion 12 is a substantially cylindrical body 16 having a bore or passage 17 extending the length thereof. The 25 front of the cylindrical body 16 is cut away at 18 whereby communication is had from the exterior to the bore 17. A rod-like member 19 is provided within the bore 17 and is movable therein. The upper end 20 of the rod 19 is adapted to accept and hold the end of a cartridge 21. A flat elongated member 22 is pivotally secured to the lower end of the rod 19 at its lower end. The flat elongated member 22 extends from within the cylindrical body 16 through opening or cut away portion 18 to the exterior thereof. The exteriorly disposed 30 end 23 of the member 22 is pivotally attached to a member 24 as at 25 which itself is pivotally mounted on a pin 26 carried at the lower end of the cylindrical body 16. A handle member 27 is provided on the pivotal member 24 whereby said member 24 can be rotated

35 about its mounting on pin 26. Pivotal movement of member 24 by handle 27 will effect longitudinal movement of the rod-like member 19 upwardly and downwardly within the bore 17 of the cylindrical body 16 by reason of its connection therewith through the linking 40 elongated member 22.

The bullet puller A comprises a base member 28 which may be made of tubular steel or steel casing and is provided with a lower reduced end portion 29 provided with exterior screw threads 30 for reception by the screw threaded bore 14 of the tool B. A lock washer or nut 31 encircles the lower reduced end portion 29 of the base member 28 and is provided with interior screw threads 32 for engagement with the screw threads 30 on the end portion 29. A set screw 33 extends through 50 a suitable screw threaded opening 34 formed in the lock washer 31 for retaining the washer in its adjusted position on the reduced end portion 29 of the base member 28.

The base member 28 is provided with a through bore 55 or passageway the lower end portion of which, that is, the portion 35 which extends downwardly from the point 36 to the lower open end of the reduced end portion 29 is of uniform diameter which is slightly greater than the diameter of the largest cartridge to be handled by the device. The upper end portion 37 of the passageway of the member 28 is downwardly tapered from the open upper end of the member 28 down to the point 36. The upper end portion 38 of the member 28 is of reduced outside diameter and is exteriorly screw threaded 65 as at 39 for engagement with the interior screw threads 40 of an upper member 41 which may be made of steel

70

tubular casing. The upper member 41 has a through bore or passageway 42 of substantially uniform diameter and the upper end portion of the member 41 is interiorly screw threaded as at 43 for receiving a top plug 44 provided with exterior screw threads 45 which are received by the screw threads 43. The plug 44 is provided with a through passageway 46 the lower end portion of which is of enlarged diameter so as to provide a downwardly facing angular shoulder 47.

An adjustable abutment 48 has its upper end held in engagement with the shoulder 47 by a coil spring 49. The abutment 48 has an external collar 50 adjacent its lower end which provides a downwardly facing shoulder 51 against which the uppermost end convolution of the spring 49 seats.

The lowermost convolution of the spring 49 seats upon a collar 52 formed on the exterior surface of a gripping device generally indicated at 53 intermediate the ends thereof. The adjustable abutment 48 is provided with a through bore or passageway 54 which communicates with the passageway 46 of the plug 44 and with the passageway 42 in the upper member 41.

The gripping device 53 comprises an elongated cylindrical portion 55 which is of substantially uniform outside diameter and has a bore or passageway 56 of substantially uniform diameter.

The lower end portion of the gripping device 53 comprises a plurality of spring fingers 57 which are joined to the lower part of the upper portion 55 of the gripping device 53 by a neck portion 58. The outside diameter of the neck portion 58 is of less diameter than the outside diameter of the upper portion 55 and the neck portion 58 has a through bore or passageway 59 which communicates with the bore or passageway 56 of the portion 55 but is of less diameter than the bore 56. The spring fingers 57 are provided by forming four slits 60 in the lower end portion of the gripping device 53 as can be seen more clearly from Figure 7 of the drawings. It will be noted that the slits 60 extend up into the neck portion 58 for substantially half of the length of the neck portion so as to impart more flexibility to the gripping fingers 57. Any desired number of gripping fingers may be provided and as shown in Figure 8 of the drawings, three such spring fingers 57 are illustrated and have been formed by providing three slits 60 in the lower end portion of the gripping device.

It will be noted particularly from Figure 3 of the drawings that the lower free end portion of each finger 57 is bent inwardly or rather extends inwardly as indicated at 61 and the inside face of each angular portion is concave or arcuate so as to properly engage the exterior surface of the bullet 62 of the cartridge 21. The lower end or fingered portion of the gripping device 53 has a through bore or passageway 63 which communicates at its upper end with the passageway 59 of the neck portion 58 and at its lower end communicates with the opening 64 between the angled portion 61 of the fingers 57. The exterior surfaces of the fingers 57 are downwardly tapered as can be seen particularly from Figures 2 and 4 of the drawings.

In the use of the device, the lower end portion 29 of the base member 28 is screwed into the arm 13 of the tool B, the amount being determined by the size of the cartridge which is to be reworked. This is previously determined and the lock washer 31 is set at the appropriate location on the lower end portion 29 and locked there by means of the set screw 33. As shown in Figures 1 and 2 of the drawing a cartridge 21 is in position ready to be reworked, that is, ready to have the bullet 62 thereof removed from its shell or casing 65. To position the bullet 62 within the gripping fingers 57, the handle 27 is rotated in a counterclockwise direction to effect an upward movement of the rod 19 thereby carrying the cartridge 21 upwardly until that portion of the bullet 62 outside of its casing is disposed

wholly within the lower end portions of the fingers 57 which will then firmly grip and hold the bullet. As the cartridge 21 moves upwardly the bullet 62 enters the opening 64 between the angled ends of the fingers 57 and the upward movement of the cartridge 21 will cause the gripping device 53 to move upwardly against the action of the coil spring 49. This upward movement will cause the fingers 57 to move upwardly towards the enlarged portion of the taper part 37 of the passageway in the base member 28. This upward movement and the pressure of the bullet 62 against the lower ends of the fingers 57 will cause the fingers 57 to spread apart and permit the bullet 62 to enter therebetween. Continued upward movement of the cartridge 21 will place the spring 49 under sufficient compression to force the fingers 57 downwardly into the narrow portion of the taper 37 so that the fingers 57 will be forced inwardly toward one another and will tightly grip the bullet 62 therebetween.

As the movement of the handle 27 is reversed to effect a downward movement of the cartridge 21 the bullet 62 will be retained by the fingers 57 and the shell or casing 65 of the cartridge which is now being moved downwardly will be separated from the bullet 62. The tightening or gripping action of the fingers 57 is automatically increased against the bullet 62 as the downward pressure movement of the shell is increased. This increased tightening action is caused by the automatic action of the coil spring 49 which moves the gripping device 53 downwardly into the narrow portion of the taper 37 thereby causing the gripping fingers to automatically tighten against the bullet 62 and to bring them to a permanent position against further downward movement while the shell 65 continues to move downwardly by action of the handle 27, thus separating the bullet from the shell.

The first cartridge shell will now be removed from the tool B and a second cartridge 21 will be positioned in the member 19 and the previously described operation will be repeated. This repeated removal of the bullet from the shell without dismantling the bullet puller can be easily accomplished as will appear from Figure 3 of the drawings which shows several separated bullets 62 being pushed in seriatum through the neck portion and the upper portion of the gripping device from which they will be moved through the passageways 54 and 46 of the abutment 48 and the plug 44 to be ejected from the bullet puller.

The tension imparted to the spring 49 may be varied by screwing the plug 44 into or out of the upper member 41 so as to move the adjustable abutment 48 downwardly into the member 41 against the tension of the spring 49 or permit the spring 49 to move the adjustable abutment 48 upwardly towards the outer end of the member 41.

Two springs could be furnished with each puller, one for friction fit for pressed in bullets and a heavier spring for crimped ammunition. The use of the heavier spring would make it possible to get a firmer hold on the crimped bullets which of course will be harder to remove.

The lock washer 31 will be pre-set for the particular caliber of cartridge being worked upon so that there is no danger that the gripping device will grip the neck of the shell instead of the bullet. The bullet puller A of the present invention is adapted to fit all conventional bullet reloading tools such as Pacific, C H Tools, Herters, Dunbar, Lyman and others.

It is obvious that various changes and modifications may be made in the details of construction and design of the above specifically described embodiments of this invention without departing from the spirit thereof, such changes and modifications being restricted only by the scope of the following claims.

What I claim is:

1. For use with a device for reworking a cartridge

composed of a shell and a bullet including means to raise and lower the cartridge, a bullet puller comprising a casing provided with securing means adapted to secure the puller to the device in a substantially vertical position, said casing having a passageway extending from the lower end thereof the intermediate portion of which is downwardly convergently tapered, a gripping device within said tapered portion of the passageway and extending thereabove for longitudinal movement therein, said gripping device having an opening in its lower end for reception of the bullet, the lower end portion of the passageway adapted to receive the cartridge when the means to raise the cartridge is actuated, said gripping device having spring fingers at said lower end, means in said passageway comprising a compression spring for holding said spring fingers in the lower part of the tapered portion of the passageway for yieldably resisting the raising of the fingers and adapted to be placed under progressively increased compression by the raising movement of the gripping device in said tapered portion of the passageway so that when the raising movement of the raising and the lowering means is arrested and the raising and lowering means is actuated to move the cartridge downwardly from the passageway the spring due to said

increased compression will also automatically move the gripping device downwardly into the lower narrow part of the tapered portion of the passageway to more forcibly engage the fingers with the bullet.

- 5 2. A bullet puller as claimed in claim 1, wherein adjusting means is operatively associated with said securing means for adjusting the position of the puller with respect to the device so that the puller can be used with bullets of various calibers.
- 10 3. A bullet puller as claimed in claim 1 wherein said casing comprises a base member, said securing means are on said base member, said casing also comprises an upper member detachably connected to said base member, and means are carried by said upper member for adjusting the compression of said compression spring.
